[57] CLAIM

The ornamental design for a display stand for massage implements, as shown and described.

DESCRIPTION

FIG. 1 is a perspective view of a display stand for massage implements showing my new design;
FIG. 2 is a right side elevational view, the opposite side being a mirror image thereof;
FIG. 3 is a top plan view thereof;
FIG. 4 is a front elevational view thereof; and
FIG. 5 is a partial sectional view taken along line 5—5 of FIG. 1.
